TEXTILE MACHINERY

Clifton Earl Hays, Pawtucket, R. I.

Application March 16, 1933, Serial No. 661,129

1. Claim. (Cl. 139—55)

This invention relates to textile machinery such as looms and has special reference to an electrically operated pattern and shed forming device for looms.

5 Looms, as generally constructed, employ either a heddle frame and harness system for the shed formation or what is known as a jacquard system and commonly such systems are mechanically actuated. The heddle frame looms, called dobby gem or cam looms employ a quite complicated head work consisting of a number of levers and some type of cam means, such as a pattern chain, for actuating the levers and thereby effecting selective lifting and dropping of the heddle frames and corresponding shed formation. The Jacquard looms also employ a complicated head works which includes a series or chain of pattern cards.

20 One important object of the invention is to provide a very simple and improved electrical device for the formation of fabric pattern and loom sheds and which will replace the complicated pattern and shed forming mechanisms such as are above described.

25 A second important object of the invention is to provide an improved device of this character wherein a roll or cylinder or a number of such rolls or cylinders are employed to effect the closing selectively of electrical circuits through electro-magnetic devices for effecting lifting of series of warp threads selectively to form the shed.

30 I am aware that rolls have been heretofore employed to close such circuits but such rolls have always been of such nature and arrangement as to form a part of each circuit.

35 A third important object of the invention is to provide a novel circuit arrangement wherein the rolls are provided with means for effecting closing of such circuits without themselves forming any part thereof, these rolls acting simply as mechanical circuit closing means.

40 A fourth important object of the invention is to provide simple mechanical means, whether or not in the form of rolls, whereby such circuits as are above described may be closed by mechanical means extraneous to the circuits.

45 With the above and other objects in view, as will be presently apparent, the invention consists of certain novel arrangements of details and combinations of parts hereinafter fully described, illustrated in the accompanying drawings and specifically claimed.

50 In the accompanying drawings like characters of reference indicate like parts in the several views, and:—

5 Figure 1 is an elevation of the left hand end of a loom equipped with this invention, all those parts not relating to the invention being omitted for the purpose of more clearly disclosing the invention itself;

10 Figure 2 is a similar front elevation of such a loom;

15 Figure 3 is an enlarged end elevation of a certain bank of contacts and a contact actuating roll as used herein;

20 Figure 4 is a plan view of one end of the arrangement shown in Figure 3;

25 Figure 5 is a detail section through the contact supporting bar and showing one pair of the contacts;

30 Figure 6 is a detail view, partly in elevation and partly in section and shows certain means for adjusting the effective action of the solenoids used herein;

35 Figure 7 is a wiring diagram showing the manner of arranging the circuit connections of the solenoids and circuit closers;

40 Figure 8 is a diagrammatic view showing an arrangement for employing two or more pattern cylinders with a single bank of solenoids, these cylinders being alined;

45 Figure 9 is a detail showing an arrangement for utilizing a plurality of pattern cylinders with a single bank of contacts, the view being somewhat schematic;

50 Figure 10 is a detail showing a schematic arrangement wherein the circuit closers are actuated by a pattern chain;

55 Figure 11 is a detail of a solenoid arrangement in a jacquard loom.

It is to be clearly understood that the several forms of the invention herein illustrated and described are merely typical of the many forms in which the invention may be embodied and that the invention is not to be restricted to the special forms now to be set forth since the structural details and arrangements will necessarily depend upon the constructions of the various looms on which the invention may be used and upon the particular service to be effected.

In Figures 1 and 2 there is disclosed a loom frame 10 of the general type used in dobby looms. The harness includes the frames 11 wherein are mounted the heddles 12 and these frames are supported by harness cords or wires 13 running over pulleys 14 rotatably supported at the top of the frame 10. The main driving shaft 15 of the loom is journalled in the lower part of the frame and a gear 16 mounted on this shaft may form the means whereby power is transmitted thereto

from a suitable driving means such as a motor. The parts just described are common to many well known looms and, by themselves, form no part of the present invention. In the simple 5 forms of such looms it is common to employ eight heddle frames and the invention has been shown in these figures as applied to a loom having this number of heddle frames although it will be obvious from what follows that it is by no means 10 restricted to any particular number of frames when used in a dobby or other like loom.

As shown in connection with the loom here 15 illustrated a bracket 17 of L-shape is supported on top of the loom frame 10 at the left hand end thereof and is held braced by suitable braces 18. Solenoids 19, equal in number to the frames 11 are butted against the vertical leg of the bracket and have shanks 20 which extend through this 20 leg so that nuts 21 may be screwed on these shanks to secure these solenoids in place. Each of these solenoids is provided with a core 22 whereto the harness cords 13 of a respective frame 11 are fastened and each core projects through a respective stem, the stems being tubular, and has an adjusting nut 23 screwed on its 25 outer end so that the drop of the frames 11 when the solenoids are de-energized may be regulated.

The roll actuated circuit closers are shown in 30 Figures 1 and 2 in their general relation to the loom and are also shown in detail in Figures 3, 4 and 5. In this part of the invention there is provided a housing 24 having slots 25 in its end walls to receive the journal ends 26 of a roll 27. As here shown this roll or cylinder 27 is provided 35 with a series of sets of circumferentially spaced holes 28 adapted to receive contact actuating pegs 29 selectively and there is provided at least one set of these holes for each of the frames 11 and its solenoid 19. One of the journals 26 has fixed thereon a gear 30 which, when the roll is dropped into place, meshes with a gear 31 wherewith is associated a sprocket 32 connected by a chain 33 with a sprocket 34 fixed on the main shaft 15. Thus the roll rotates in 40 timed relation to the main shaft and, since the entire loom is actuated from this shaft, the roll rotates in timed relation to the movements of the shuttle so that, as will be presently understood, the shed is opened just prior to the pick 45 of the shuttle in throwing the weft. Journalled in the ends of the housing is a bar 35 preferably of insulating material. This bar is arranged to rotate in said housing ends and is held in adjusted position by nuts 36. On top of this bar 50 is fixed a series of spring contacts 37 preferably termed the movable contacts and equal in number to the sets of holes 28. Below each of these contacts is a second spring contact 38 which are termed the fixed contacts. Each contact 37 has 55 mounted on its free end a striker piece 36a wherewith a peg or pin 29 placed in one of the corresponding sets of holes 28 engages as the roll is rotated. Thus the contacts 37 are closed on the contacts 38 selectively. Each contact 37 is connected by a wire 39 with one terminal of a respective solenoid 19 while the remaining terminals of the solenoids are connected in multiple to a current supply line 40. Similarly, the contacts 38 are connected in multiple to a second supply line 60 41. By tilting the bar 35 to a suitable angle by loosening the nuts 36 the time the contacts 37 remain closed on the contacts 38 may be regulated since by this means the pins 29 will remain 65 in engagement with and depress the contacts 37 a greater or lesser time.

Now, by properly positioning the pins 29 in the holes 28 the contacts may be closed in any desired order. As each contact is closed a circuit will be established through the solenoid controlled by that contact and the corresponding harness or heddle frame will be raised and the shed formed by lifting the desired group of warp threads controlled by that heddle frame. Thus any desired pattern capable of being worked on the particular loom may be formed.

At times it may be desirable to weave a pattern too long to be controlled by the number of holes in one set of the holes 28 extending circumferentially around the roll since, obviously, after the roll has made a complete rotation there 15 will be a repetition of the pattern pegged out on that roll in the arrangement above mentioned.

In order to provide for a greater number of picks before a repeat than is possible under these conditions several devices now to be described 20 may be used.

As shown in Figure 8 several of the rolls 21 may be mounted on the same shaft each associated with its set of contacts 37 and 38 may be used. In this case one terminal of each solenoid 25 19 has connection with corresponding contacts 37 of the several sets in multiple by wires 39a while the remaining terminals of the solenoids are connected in multiple to the line wire 40 as before. The line wire 41 in this case is connected 30 to a wiping contact 42 which bears on a conductive disk 43 rotated from the shaft of the rolls 27 by gearing 44. An insulating strip 43a extends around part of the periphery and spaced around the periphery are wiping contacts 45 each of 35 which is connected to all of the contacts 37 of a respective set by a wire 46. The upper wiping contact 45 as shown in Figure 8 is engaged with the electrically charged disk 43 through the positive line wire 41. This position of the disk, as 40 will be observed, governs the positive side of the contact opposite the left hand cylinder 27, and assuming that the first pair of contacts 38 were depressed, positive current would be caused to flow from its source through line wire 41, contact 42, upper wiping contact 45 and through the contact 38 to a solenoid 19 for return over the negative wire 40. When the disk 43 is rotated to place the lower wiping contact in electrical engagement with the disk, positive current will 45 be caused to flow from the source through line wire 41, contact 42, disk 43, lower brush 45 and wire 46 to furnish positive current to any one of the contacts which might be closed on the right hand cylinder 27 and should any one of the contacts 38 be closed for engaging the contact 37, this positive current would flow through a coil 19 and return over wire 40 to the negative side of the source of supply of electrical energy.

In the form shown in Figure 9 spiders 46 are 50 mounted on a shaft 47 and driven by Geneva gearing 48 suitably actuated by gearing (not shown) from the main shaft. The rolls 27 are journalled in the ends of these spiders and the gears 30 of these rolls are thus brought successively into mesh with the gear 31 and in position to actuate the contacts 37 to close on the contacts 38.

In the form shown in Figure 10 the rolls are 55 replaced by an endless chain of bars 49 having holes 50 and pins or pegs 51 similar to the holes and pins of the rolls and arranged to selectively close the contacts 37 on the contacts 38 as before. The chain is supported on suitable toothed drums 60 56

52 driven by suitable gearing (not shown) from the main shaft of the loom.

With any one of these arrangements a pattern covering any practical number of weft picks may 5 be arranged for before a repeat.

In Figure 11 is shown an arrangement of sole-
10 noid for a jacquard loom wherein the solenoid
19a is disposed vertically and heddle wires 53
are connected directly to the core 22a. Obvi-
ously, although but a single solenoid is here
15 shown, a number of such solenoids will be em-
ployed nested as closely together as is practi-
cable and the core of each solenoid will have a
selected group of heddle wires carried thereby
20 so that complicated patterns may be formed by
this means just as with the well known cards of
a jacquard loom.

It will be seen that, by means of this invention
25 a much wider variety of patterns may be ob-
tained from an ordinary dobby loom with me-
chanical head works. Furthermore, the head
works and harness of a dobby loom may be re-
placed by solenoids and heddle wires as in Fig-
ure 11 and such a loom readily converted into a
20 loom of the jacquard type.

There has thus been provided a simple and
efficient device of the kind described and for the
purpose specified.

It is obvious that many minor changes may

be made in the form and construction of the in-
vention without departing from the material
principles therein involved. It is not, therefore,
desired to confine the invention to the exact
5 forms herein shown and described but it is de-
sired to include all forms which properly come
within the scope claimed.

What is claimed as new is:—

In a loom or the like, a series of heddle ac-
tuating solenoids, a circuit for each of said sole-
10 noids including a normally open circuit closer,
said circuit closers each consisting of a fixed
contact and a movable contact and being arranged
in a bank, a roll positioned parallel to the bank
15 of circuit closers and provided with a series of sets of circumferentially spaced holes, each set
being alined with a respective circuit closer, and
pegs selectively positionable in said holes and en-
gageable with the movable circuit closers to close
them on the fixed circuit closers whereby to 20
effect selective energization of said solenoids, a
second similar roll, said rolls being mounted to
move bodily into and out of position to actuate
the circuit closers, means to effect movement of
the rolls successively into circuit closer actuated 25
position, and means to drive the roll in such po-
sition, and means to drive the roll in such po-

C. EARL HAYS.
